UNITED STATES PATENT OFFICE.

BERT RIVKIN, OF NEW YORK, N. Y., ASSIGNOR, BY DIRECT AND MESNE ASSIGNMENTS, OF ONE-FOURTH TO LEONA SHERMAN AND ONE-SIXTH TO SELMAN LISS, BOTH OF NEW YORK, N. Y., AND ONE-SIXTH TO LEOPOLD TROPP AND ONE-SIXTH TO MORRIS M. TURITZ, BOTH OF BROOKLYN, NEW YORK.

WINDOW-SHADE ROLLER.

1,095,177.

Specification of Letters Patent. Patented Apr. 28, 1914.

Application filed March 21, 1910. Serial No. 550,681.

To all whom it may concern:

Be it known that I, BERT RIVKIN, a citizen of the United States, and a resident of New York, borough of Bronx, in the county 5 of New York and State of New York, have invented certain new and useful Improvements in Window-Shade Rollers, of which the following is a specification.

The objects of this invention are to provide a new and simple means for controlling the operation of a window shade, whereby the shade may be operated entirely independent of itself and thereby greatly increase the life of the shade, also to prevent 10 the soiling of the same by handling, and to prevent the unrolling of the shade by the breeze when the window is left open and the shade is allowed to blow back and forth.

The further objects are to provide an attachment which is simple and inexpensive to manufacture, and which does not need to be adjusted, and will not get out of order, and will hold the shade in any desired position, and to also provide a fixture which 15 will not allow the shade roller to slip out of its sockets and be pulled down when the shade is being raised or lowered.

The foregoing features will be clearly seen by referring to the drawing forming a part 20 of this specification, of which—

Figure 1 is a perspective view of my invention; Fig. 2 is an enlarged detail perspective view; Fig. 3 is an enlarged longitudinal section, showing the arrangement 25 of the several parts; Fig. 4 is a transverse section on line $x-x$ of Fig. 3; Fig. 5 is a detail perspective view of one side plate; Fig. 6 is a similar view of the other side plate; Figs. 7 and 8 are detail perspectives 30 of the spring or friction device; Fig. 9 is one of the journals which forms a drum; Fig. 10 is one of the guides or sides of the drum; Fig. 11 is a perspective view of one 35 of the journals; Fig. 12 is a longitudinal section of a modification of my invention; Figs. 13 and 14 are perspective views of the side plates and the guide or hood which forms the bracket shown in Fig. 12; Fig. 15 is a perspective view of the spring used in 40 Fig. 12; and Figs. 16 and 17 are a modification of the journal and end plate for the shade, which may be used in place of the 45

journal shown in Fig. 9; Fig. 18 is a section of one end of a shade roller showing means for preventing the roller from splitting, and is used when the shade is very 55 large or heavy.

It will be seen by referring to the drawings that I have provided a simple and effective shade roller, which consists of the 60 ordinary wooden roller 2, to which the shade 2' is attached by any suitable means, having journals 3 and 4 which have enlarged outer ends 5, which prevent the journals 65 from being drawn out of their bearings and thus keep all of the parts assembled after the flattened and tapering ends 6 have been driven into the roller 2.

By referring to Fig. 3, it will be seen 70 that the journal 3 has a long body portion 8. This is to allow for adjusting the side plates 9 and 10 to the window frame, as indicated by dotted lines. This adjustability has been found very advantageous, owing 75 to the warp of the wood and the unevenness in the building of window frames, and it overcomes a great annoyance due to the swelling and shrinkage of the wood in various kinds of weather, which causes the rollers now in use not to work in damp weather 80 and to fall from their bearings in dry weather. These annoyances are overcome by the self adjusting feature of this bearing.

The journal 4 is provided with a hole 11 through which is passed and secured a cord 85 or cable 12, a sufficient portion of which has been wound on the journal to equal the length of the shade and also in the same direction as the shade is wound on the roller 2. The cord 12 is allowed to hang in the 90 form of a loop within easy reaching distance, and the other end is passed through the hole 11 in the opposite direction to the first end and secured in any suitable manner. The journal 4 is further provided with 95 a pair of guide plates 13 and 14 for guiding the rolling up of the cord or cable 12, and, if desired, for cheapening the manufacture of the device, the guide plates may have a hole 15 punched in them for the reception of the ends of the cord or cable 12 instead of the hole 11 in the journal. If this is done one end of the cord 12 will be secured 100 in the guide plate 13 and then the cord

wound on the journal the same as before described and the other end secured to the guide plate 14.

The side plate 10 is provided with an 5 elongated opening 16, which is at an angle of about 45 degrees to its perpendicular axis. The upper end of this slot or opening terminates in an enlargement 17 the lower end of which passes around the corner and

10 then downwardly or parallel with the perpendicular axis of the side plate, forming a side opening 18. This opening 18 is to allow the locking members 19 and 20 of the friction spring 21 to be passed into position.

15 The friction spring 21 is provided with a pair of downwardly extending ears 22 which overlap the outside of the guide plates 13 and 14, and these ears 22 prevent the spring 21 from becoming misplaced. The spring 21

20 is made so as to have a firm bearing upon the periphery of the side guides, and this friction causes the roller to be locked in any position that is desired. The spring 21 is held in position by having its locking lugs passed

25 through the opening 18, and the body 21 being passed into the slot 16, the spring is then drawn forward until the lug 19 presses against the inside of the side plate 10 and the lug 20 is located in the enlargement 17.

30 It will thus be seen that the lug 20 prevents the spring from being drawn out of the slot in one direction and that the lug 19 prevents it from being drawn out in the other direction. The upward pressure caused by

35 the side guides 13 and 14 of the journal, and the ears 22 of the spring prevent it from being pushed back in the slot and becoming loose. It will thus be seen that all the parts of the device interlock with each other after

40 being assembled, without the aid of bolts, screws, rivets or solder, which are the expensive parts of manufacturing.

The side plates 9 and 10 are provided with openings 23 for the reception of ordinary 45 wood screws 24 to fasten them to the window frame, and are further provided with a boss 25 which forms an extension bearing for the journals to allow for the variation in the window frames.

50 By referring to Figs. 12, 13 and 14, in which I have shown a modification, it will be seen that I have provided the side plate with an extension guide 26, which, taken in connection with the side plate 27, takes the

55 place of the guide plates 13 and 14 to insure the proper winding of the cord or cable 12. The side plate 27 is also provided with two partial perforations 28, and the metal which is forced out of these perforations is formed

60 into tongues 29 which are so bent as to form a slot 30 between the inner surfaces of the plates 27 and their outer surfaces. This slot 30 takes the place of the slot 16 for the purpose of maintaining the spring 31, which is

65 bent at the top forming a locking portion 32.

It will be noted that in this construction the spring 31 bears directly on the end of the journal 4 instead of on the guide plates. The friction is thus caused by the enlarged end 5 of the journal 4 being pressed against the bearing 36, and also the pressure of the spring on the end of the journal, but the function is the same as in the device before described.

The guide 26 of the side plate 27, which is shown in the form of a partial hood with an opening 33 in the bottom for the cord or cable 12 to pass through, may also be, if desired, made a complete hood or housing without affecting the operation of the device as long as it has the opening 33 in it. This guide 26 may be made integral with the side plate, or, as I have shown it, with the side plate, having openings or slots 34 for the reception of tongues 35 of the guide or hood, which when passed through the slots 34 are upset or bent over to hold the guide wedged in its proper position.

Fig 16 is a modification of the journal 4, the difference being in the end portion 37, which is made square in section and to fit the opening 38 of the plate 39 shown in Fig. 17. This plate or disk is provided with a plurality of countersunk holes 40 for wood screws to fasten the same to the end of the roller 2; and if desired this plate 39 may be made in the form of a cap, that is to have a flange to fit over the end of the roller 2, as shown in Fig. 18, to prevent the same from splitting. This form of journal and end protection for the roller 2 is used in cases of very large shade rollers such as are used in display windows of stores.

It will be seen by the foregoing description that many similar modifications may be made to facilitate the manufacture of these devices and to meet the demands of the various situations and designs of window frames without departing from the spirit of my invention, and I wish to reserve such rights to make any necessary changes.

The operation of this device is extremely simple. After the shade has been placed in position, by pulling on the cord 12 which is wound on the journal, it will cause the roller to revolve and unwind the shade, and at the same time cause the exact amount of the other end of the cord to wind up in the opposite direction on the journal as has been unwound by the pulling of the cord. It will thus be seen that by pulling on either one side or the other of the loop 41 the shade may be either rolled up or unrolled, as desired by the operator, without touching the shade itself, and the friction spring will hold the shade securely in any position in which it is left.

I claim as my invention:

1. A window shade having elongated journals, one of which acts as a drum, a side

plate, a hood mounted upon the side plate, the side plate and hood having bearings for the journal and acting as guides for the cord or cable wound upon the journal for rotating the roller in either direction, and means for holding the shade or roller in any position.

2. A window shade having a roller with elongated journals, one of which acts in the capacity of a drum, a side plate in the form of a bracket and acting as a guide for the cord or cable which is wound upon the journal, and capable of rotating the roller in either direction, means for holding the shade at any desired height, and an automatic adjusting bearing, the adjustability being in line with its axis and movable independently of the holding or operating means of the roller.

20 3. A window shade having a roller with elongated journals, one of which acts in the capacity of a drum, a side plate in the form of a bracket and acting as a guide for the cord or cable which is wound upon the journal and capable of rotating the roller in either direction, means for holding the shade

at any desired height, a second side plate with an extended bearing which acts with one of the elongated journals and compensates for the varying widths of windows, 30 and an automatic adjusting bearing, the adjustability being in line with its axis and movable independently of the holding or operating means of the roller.

4. A window shade, having elongated 35 journals, one of which acts as a drum, a side plate, a hood mounted upon the side plate, the side plate and hood having bearings for the journal and acting as guides for the cord or cable wound upon the journal for 40 rotating the roller in either direction, means for holding the shade or roller in any position, a self-adjusting bearing, the adjustability being in line with its axis and movable independently of the holding or operating 45 means of the roller, and means for keeping all the parts assembled upon the roller when the shades are being transported.

BERT RIVKIN.
